UNITED STATES PATENT OFFICE.

JOHN KOLUMBUS, OF PHILADELPHIA, PENNSYLVANIA.

WINDOW SCREEN.

Application filed July 18, 1925. Serial No. 44,542.

One of the objects of the present invention is to provide a window screen having an improved double frame construction so that the screen mesh can be held between the two frame sections, preferably being permanently attached to one of them.

Another object of the invention is to provide improved means adapted to be manually operated from near the vertical center line of the screen for moving vertical adjusting strips at the sides of the screen.

Further objects of the invention will be apparent from the following specification and claim.

15 In the accompanying drawing, I have shown the embodiment of the invention which I now deem preferable, but it will be understood that the drawing is for illustrative purposes only and that various 20 changes and substitutions within the scope of the appended claim may be made without departing from the spirit of the invention.

Of the drawings:

25 Fig. 1 is a perspective view of a screen embodying the invention.

Figs. 2 and 3 are perspective views showing the two main sections of the screen detached from each other and separated.

30 Fig. 4 is a sectional view on an enlarged scale taken along the line 4—4 of Fig. 1.

Fig. 5 is a sectional view on an enlarged scale taken along the line 5—5 of Fig. 1.

Referring to the drawing, 1 and 2 represent the two sections of the frame, the sections being identical in size and preferably similar in construction. Preferably and as illustrated each frame section comprises vertical side members 3, 3, and horizontal top 35 and bottom members 4, 4, these several members being rabbeted together at the corners. The two frames are connected together by any suitable means such as screws and the wire mesh 5 is clamped between the two sections. Preferably as clearly shown in Fig. 2, the wire mesh is permanently attached, as for instance by tacking, to one of the frame members, in this case the frame member 1. While I do not limit myself to any particu-

45 lar means for connecting the two frame members together, I prefer to use at least at some points screws 6 which extend through one frame member into threaded bushings 7 fixed in the other member.

50 While these screws 6 are provided at some points, ordinary wood screws may be used at other points.

Vertically extending adjustable strips 8, 8 are provided at the two sides of the screen and preferably these are located in grooves 60 formed by similar rabbets 9, 9 in the companion side elements of the two frame members. The construction is clearly shown in Fig. 4. It will be understood that the grooves formed by the two rabbets are of sufficient width to permit the adjustable strips to be freely movable as hereinafter described. Preferably each of the strips 8 is made up of three separate pieces of wood glued together as shown in Fig. 5 so as to prevent warping.

For moving the two adjustable strips simultaneously I provide two separate manually operable devices at the top and at the bottom of the screen respectively. As these 75 two devices are identical in construction a description of one of them will suffice for both. Each of the adjacent companion top or bottom members of the two frames is provided with two similar recesses 10, 10 in 80 line with each other and separated by an abutment 11. The recesses of the two members are in register and slidably mounted in the respective recesses 10, 10 are blocks or plungers 12, 12 to which are connected horizontally extending rods 13, 13. These rods lie in grooves formed in the two adjacent members of the frame and at their outer ends are threaded into or otherwise connected with the beforementioned adjustable strips 85 8, 8. Springs 14, 14 are seated in the respective recesses 10, 10 and these springs bear against the two plungers 12, 12 and also against the abutment 11. The springs tend to hold the plungers in their outermost 90 positions as shown thus holding the adjusting strips in their outermost positions.

One of the frame elements is provided with slots 15, 15 adjacent the plungers 12, 12 and finger grips 16, 16 are secured to these 100 plungers and extend outward through the slots. Preferably as shown the finger grips are threaded into the respective plungers. I prefer to provide a metal plate 17 with slots 18, 18 therein registering with the slots 15, 15. This metal plate serves to protect the edges of the slots 15, 15 and also improves the general appearance of the screen. By simultaneously gripping the two pairs of finger grips 16, 16 the vertical adjustable 110

strips at both sides of the screen will simultaneously be drawn inward thus allowing the screen to be put in place or removed. Obviously when the pressure on the finger grips is removed the springs 14, 14 will force the adjusting strips outward either until they engage the window casing or until the plungers 12, 12 engage the ends of the recesses 10, 10.

10 From the foregoing description it will be apparent that the double frame construction not only gives great strength, but also makes it possible to easily replace the wire mesh when necessary. It will further be clear 15 that the screen can be easily and quickly adjusted so as to be put in place in a window or removed therefrom. The finger grips serve not only to adjust the adjustable strips but also serve as means whereby the entire 20 screen may be held while being put in place or removed.

What I claim is:

A window screen comprising in combination two similar frame sections each of 25 which comprises a top, a bottom and a pair of side rails; rabbets formed on the side rails of each frame section; a recess formed in each of the top and bottom rails of each frame section approximately at the center 30 thereof; a transverse abutment formed at the center of each recess; a semi-circular groove in each end of each of the top and bottom rails, extending between each of the

opposite ends of the said recess and the base of the rabbet of the respective side rails; a 35 series of internally threaded bushings in one of said frame sections; a series of screws adapted to pass through the other frame section and to cooperate with said bushings to secure the frame sections together whereby 40 the said side rail rabbets of the respective frame sections cooperate to form side grooves in said screen, the said recesses, abutments and semi-circular grooves of each frame section cooperatively register with each other to 45 form respectively a singular recess and abutment and singular circular openings connecting the said recesses and said side grooves; strips in said side grooves laterally adjustable with respect to said screen; a plunger in 50 each of said singular recesses between the end thereof and the abutment therein; a round rod in each of the singular circular openings cooperatively connecting one end 55 of each of said plungers with one end of one of said adjustable strips; a spring between the opposite end of each plunger and one side of the abutment; a slot formed in the top and bottom rails of one of said frame sections communicating with the said singular recess therein; finger grips attached to each of said plungers and extending through 60 said slot; and a wire mesh fabric secured to one of said frame sections and gripped between the pair thereof.

JOHN KOLUMBUS.
